HERBERT ALFRED HUMPHREY, OF BILLINGHAM, STOCKTON-ON-TEES, ENGLAND, AS-
SIGNOR TO IMPERIAL CHEMICAL INDUSTRIES LIMITED, OF LONDON, ENGLAND, A
BRITISH COMPANY

METHOD OF INTRODUCING LIQUIDS OR MIXTURES THEREOF WITH SOLIDS INTO
HIGH PRESSURE APPARATUS

Application filed August 25, 1927, Serial No. 215,500, and in Great Britain September 27, 1928.

This invention relates to a method of introducing materials, such as liquids or mixtures of solids with liquids, into high-pressure vessels, especially those in which pressure of 100 atmospheres or over are employed e. g. for processes of destructive hydrogenation.

According to the invention, the material is displaced from an auxiliary high-pressure reservoir into the main high-pressure vessel by means of a fluid, preferably a liquid, which is independent of and does not under the working conditions mix with the material to be treated to any substantial extent. The displacing fluid is preferably employed in a circuit, by drawing it from an auxiliary fluid vessel (which may be at low pressure), pumping it into the auxiliary reservoir and exhausting it from the latter after it has performed its function of displacing the material from the reservoir into the main high-pressure vessel.

Two forms of the invention are illustrated in the accompanying diagram. Figure 1 illustrates the direct displacement of liquid or semi-liquid material by means of another liquid, immiscible with the first. In Figure 2, a similar device employing a loose piston in order to prevent mixing of the displacing fluid with the material, is shown.

Referring to Figure 1, A is the main high-pressure vessel, B the auxiliary reservoir and C the auxiliary fluid vessel. The working fluid in this case is oil, which is stored in C and which can be pumped under pressure into B by means of the pump D. The reservoir B can be emptied of oil by opening the lower valve E, which allows the oil to return to C. The level of oil in C is conveniently ascertained by a gauge F which thus permits of following the level in the reservoir B.

The reservoir B being empty and the valve E shut, the charging valve G is opened and a charge of material is allowed to enter. The valve H, which communicates with the atmosphere, may be open during this time. Valve G is then shut and valve I is opened to admit oil to the space above the charge, the air being expelled through H which is shut as soon as the oil fills the vessel. Pressure is then brought to bear upon the oil by operat-

ing the pump, and valve J, communicating with the main high-pressure vessel, is opened. The charge is forced slowly into A and when the oil level reaches that of E, valves I and J are closed, and E and H are opened to allow the oil to run back into C. The cycle is then started afresh.

In the form of the invention shown in Figure 2, a loose piston K is employed in the auxiliary reservoir to prevent mixing of the material to be charged into A and the oil pumped from the auxiliary fluid vessel. The auxiliary vessel is then constructed of two cylinders of different bore and the double piston K sliding therein has heads of corresponding diameter, to enable the piston to be hydraulically operated in either direction in a positive manner. The operation of charging the vessel A is as follows:

Assuming B to contain a charge of material, the valve G is closed and J is opened to enable the piston to force the charge into A. The piston is caused to move forward by pumping oil from C by means of the pump D to the chamber N the valves L and M being connected to the pressure and exhaust of D respectively. The large end of the piston is exposed to oil pressure and this facilitates the operation of the pump against the high pressure prevailing in A. When the piston has reached the end of its stroke, J is shut, the valves L and M are changed over to connect to exhaust and pressure respectively, and G is opened. A fresh charge of material is thus sucked in while the piston is moving back and when subsequently G is closed and J opened, the cycle is ready to start afresh. The material introduced into A may be submitted in this vessel to destructive hydrogenation, i. e. to the action of hydrogen under high pressure at an elevated temperature.

In the appended claims I use the term "semi-liquid material" to mean pastes, sludges or suspensions of finely ground material in liquids such as e. g. suspensions of coal in oil.

I declare that what I claim is:

1. Method of introducing semi-liquid materials into high pressure vessels which comprises running said semi-liquid material into an auxiliary high pressure reservoir, forcing

into said reservoir from a liquid storage tank, a liquid under a pressure of at least about 100 atmospheres, injecting said semi-liquid material into the high pressure vessel, and when the auxiliary reservoir is empty of semi-liquid material, running the displacing liquid back by a different path to the storage tank.

2. Method of introducing semi-liquid material into high pressure vessels which comprises running the semi-liquid material into an auxiliary high pressure reservoir, forcing into said reservoir from a liquid storage tank a specifically lighter liquid, displacing said semi-liquid material in a downward direction into said high pressure vessel thereby, and when the auxiliary reservoir is empty of semi-liquid material, running the displacing liquid back to the storage tank.

3. Method of introducing semi-liquid material into high pressure vessels, which comprises pumping the said semi-liquid material into an auxiliary high pressure reservoir, said reservoir being open to the atmosphere, closing the connection to the atmosphere and opening a connection to the high pressure vessel, forcing into said reservoir from a liquid storage tank a specifically lighter liquid, displacing said semi-liquid material into said high pressure vessel in a downward direction, then when said auxiliary reservoir is empty of semi-liquid material, closing said connection to said high pressure vessel, and opening said connection to atmosphere and running said liquid back to said storage tank and repeating the cycle.

In witness whereof, I have hereunto signed my name this fifth day of August, 1927.

HERBERT ALFRED HUMPHREY.
